CLAIM

The ornamental design for a battery disconnect switch, as shown and described.

DESCRIPTION

FIG. 1 is a front perspective view of a battery disconnect switch, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view showing the battery disconnect switch in a split state;

FIG. 10 is an enlarged detail view of area 10 in FIG. 1; and,

FIG. 11 is an enlarged detail view of area 11 in FIG. 9.

The broken lines in the drawings illustrate the portions of the battery disconnect switch, which form no part of the claimed design.

The dash-dot-dash broken lines encircling the enlarged views are for annotative purposes only and form no part of the claim thereof.

1 Claim, 11 Drawing Sheets
